UNITED STATES PATENT OFFICE.

WILLARD J. ANDREWS, OF ST. LOUIS, MISSOURI, ASSIGNOR OF ONE-HALF
TO JOHN URI MUSICK, OF SAME PLACE.

DESIGN FOR A COOKING-STOVE.

SPECIFICATION forming part of Design No. 18,263, dated April 24, 1888.

Application filed December 19, 1887. Serial No. 258,417. Term of patent 14 years.

To all whom it may concern:

Be it known that I, WILLARD J. ANDREWS, a citizen of the United States, residing at St. Louis, in the State of Missouri, have invented and produced a new and original Design for Stoves, of which the following is so full, clear, and exact a description as will enable others skilled in the art to which my invention appertains to make and use the same, reference being had to the accompanying drawing.

The leading feature of my design consists in the peculiar ornamentation of the front and top of the stove, as more fully hereinafter described.

15 A indicates the stove, which is rectangular in general contour, and has a water-reservoir, B, and coal-box D at one side. The edges of the top of the stove are slightly beveled, as shown, inclining outwardly from top to bottom, and such beveled edges are ornamented by depressed configurations, each comprising a small semicircular figure, a, opening at the upper corner of the edge of the stove-top, a smaller semicircular figure, a', opening at its 20 top into the lower curved face of said figure a and its closed end extending nearly or quite to the lower corner of the edge of the stove-top, and a deeper depressed figure, a'', semicircular in shape, within and concentric with the said figure a.

25 The flat rack B extends across the rear face of the stove, and is formed of two side pieces, b b, the forward lower edges of which are struck on a curve and thence rise vertically, the lower shelf, b', upper shelf, b'', and back b'', the lower shelf being formed of bars, as shown.

35 The respective doors of the stove are formed with raised edges d around the outer faces of the same, the said edges d being ornamented 40 with raised figures d', forming ornamental borders for the said door.

The centers of the fire-box door E and the ash-box door F are ornamented by rectangular

depressions e f and the door F by a cross-bar, f', secured to lugs at the front of said door. 45 The intermediate door, G, is ornamented by openings g.

The oven-door H has at its center a depressed crescent, h, merging at one end into a depressed five-pointed star, h'. The front of 50 the stove below the oven-door is provided with a small ornamental door, I, and the whole lower front portion of the stove is formed of a plate, K, ornamented at its edges by raised borders L, having ornamental screws at suitable intervals.

I claim—

1. In a design for a stove herein shown and described, the front thereof having an ornamental top the edges of which are beveled and provided with depressed configurations, each comprising a small semicircular figure, a, opening at the upper corner of the edge of the stove-top, a smaller semicircular figure, a', opening at its top into the lower curved face 65 of said figure a and its closed end extending nearly or quite to the lower corner of the edge of the stove-top, and a deeper depressed figure, a'', semicircular in shape, within and concentric with figure a, substantially as specified. 70

2. In a design for a stove herein shown and described, the ornamental front having the respective doors provided with raised ornamental borders with depressed centers, substantially as specified. 75

3. In a design for a stove herein shown and described, the oven-door consisting of an ornamental border surrounding the central portion thereof, and a depressed crescent merging into a star at the center, substantially as shown. 80

In testimony whereof I affix my signature in the presence of two witnesses.

WILLARD J. ANDREWS.
